DESIGN FOR A TRANSFORMER

Richard B. Shimer, Wurtsboro, N. Y., assignor to
Kenyon Transformer Co., Inc., New York, N. Y.,
a corporation of New York

Application April 26, 1940, Serial No. 91,987

Term of patent 14 years

To all whom it may concern:

Be it known that I, Richard B. Shimer, a citizen of the United States, residing at Wurtsboro, in the county of Sullivan and State of New York, have invented a new, original, and ornamental Design for a Transformer, of which the following is a specification, reference being had to the accompanying drawing, forming a part thereof.

Figure 1 is a perspective view of a transformer showing my design; and

Figure 2 is a top plan view thereof.

The bottom of the transformer is substantially plain.

I claim:

The ornamental design for a transformer, as shown and described.

RICHARD B. SHIMER.
